HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

FLUID-TRANSLATING DEVICE.

1,421,842.

Specification of Letters Patent. Patented July 4, 1922.

Application filed September 14, 1914, Serial No. 861,631. Renewed December 30, 1921. Serial No. 526,030.

To all whom it may concern:

Be it known that I, HENRY F. SCHMIDT, a citizen of the United States, and a resident of Swarthmore, in the county of Delaware and State of Pennsylvania, have made a new and useful Invention in Fluid-Translating Devices, of which the following is a specification.

This invention relates to fluid translating devices and particularly to devices for maintaining a high vacuum in condensers or similar apparatus.

An object of the invention is to produce a fluid translating device of the kinetic type in which means are employed for maintaining the operation of the device substantially constant for practically all varying conditions.

A further object is to produce a fluid translating device employing the kinetic or velocity energy of the motive fluid delivered to it in transferring fluid from a region of lower to a region of higher pressure, which automatically adjusts itself to variations in the quantity of fluid conveyed, thus preventing fluctuations of pressure in either the region of lower or higher pressure.

These and other objects, which will be made apparent to those skilled in the art throughout the description of the invention, are attained by apparatus embodying the features herein described and illustrated in the drawings accompanying and forming a part of this application.

The single sheet drawing is a sectional view of an ejector embodying my invention.

In fluid translating devices such, for example, as ejectors, which employ a stream or jet of fluid as the propelling medium for exhausting fluid from a receptacle, or for transferring fluid from a region of lower to a region of higher pressure, it is necessary to construct the fluid conducting passage, through which the propelling medium and the medium entrained move in accordance

with the following equation: $\frac{AV}{v'} = W$. In

which A equals the cross sectional area of the tube at any point; V the velocity of the combined media passing that point; v' the specific volume of the combined media; and W a constant which is equal to the weight of the media passing the point, in a unit of time.

It will be apparent, therefore, that if the

fluid translating device or ejector is designed to attain a high degree of compression under one set of operating conditions, it will not be suitable for starting or for operating under varying conditions. In order, therefore, to render the ejector effective for all varying conditions, it is necessary to vary the dimensions of the fluid conducting or delivering passage in accordance with variations in the conditions, or to effect a change, which is the equivalent of changing the dimensions of the passage, to meet the varying conditions.

In the present application I have illustrated ejectors in which means are employed for varying the effective area of the throat of the fluid delivering passage or diffuser in response to variations in the volume of fluid passing from the region of lower pressure through the diffuser to the outlet, or to the region of higher pressure. It is well known that the pressures existing throughout the diffuser vary in response to variations in the amount of fluid traversing the diffuser, and it is also well known that in order to prevent upsetting when the ejector is operating under light load, or at less than its designed capacity, it is necessary that the pressure at each point along the diffuser remain substantially constant. I therefore provide means which is responsive in its operation to variations in diffuser pressure and which operates to vary the effective throat or the effective area of the diffuser.

The apparatus illustrated as an embodiment of my invention includes a diffuser 3, to which motive fluid is delivered through a main divergent nozzle 4, located axially with relation to the diffuser and to which fluid is also adapted to be delivered through a series of accelerating nozzles 5, which are preferably located around the main nozzle 4 and are preferably so inclined that the streams of fluid delivered from them combine with the stream issuing from the nozzle 4 at the throat of the diffuser 3. As shown, each of the nozzles 5 projects into and is adapted to discharge motive fluid through a separate suction and combining chamber 6, which is provided with a port 7, adapted to communicate with the vessel to be evacuated, or with the region of lower pressure. A separate diffuser 8 communicates with each chamber 6 and is located axially with reference to its corresponding nozzle 5, so that

fluid discharged from the nozzle passes through the diffuser after having passed through the chamber. The diffusers 8 form in effect a combining chamber for the nozzle 4 and consequently communicate with the diffuser 3.

Since, in order to provide an effective ejector, it is necessary that the product of the area of the conducting passage and the 10 velocity of the medium divided by the specific volume of the medium shall equal a constant, which is the weight of medium passing through the ejector in a unit of time; and since it is also desirable to maintain a constant pressure in the chamber 8, the specific volume of the medium will therefore be maintained constant and since the nozzle or nozzles 4 and 5 discharge from a constant initial to a constant final pressure, 15 i. e., the pressure in the chamber 8, it is evident that, in order to maintain a condition of stable equilibrium in the diffuser, the area of the diffuser must be varied in direct proportion to the variations in the 20 weight of the medium passing through it.

If the area of the throat of the diffuser is not varied, as above set forth, it is evident that, since the weight of the medium is varying while specific volume of the medium 25 in the chamber 8 remains constant, the velocity of the medium passing through the throat must vary, that is, decrease if the weight of medium passing decreases, and increase if the weight of medium passing 30 increases. In order to compress or discharge medium from the space 8 through the outlet of the diffuser 3, a definite amount of work per unit weight of medium must be performed; and this work of compression or 35 translation must be provided by the kinetic energy of the medium at the entrance of the diffuser. Consequently if the velocity of the medium at the entrance decreases so that the kinetic energy of the medium is less than 40 the work necessary to move the medium from the lower to the higher pressure, it is apparent that the medium will not be discharged from the outlet of the diffuser. Under such conditions the velocity of the medium in the diffuser will immediately drop 45 to zero, and not only no work of compression will be accomplished, but fluid will flow from the region of higher pressure, or the outlet end of the diffuser, into the region 50 of lower pressure, or the chamber 6. This result is technically known as upsetting, to which reference has been previously made.

The nozzle 4 is so arranged that it will move to different positions with relation to 55 the throat 10 of the diffuser 3 for the purpose of varying the area of the throat 10, and likewise in effect shifting the throat 10 of the diffuser 3 to the throat 12 of the nozzle 4, when the nozzle is in such a position 60 that the divergent portion of the diffuser 3

combines with the nozzle to form a single converging, diverging nozzle. It will be understood that under these conditions the nozzle 4 does not actually touch the throat 10 of the diffuser 3, but assumes a position 70 as indicated by the dotted lines in the drawing. This provides a restricted annular opening for the admission of fluid from the chamber 8.

As illustrated, this is accomplished by 75 providing the nozzle 4 with a tubular fluid delivery passage 13, which is slidably mounted on a body of the ejector and is provided with a piston 14, operating in a cylinder 15, for moving it to different longitudinal positions. One end of the cylinder 15, as for example, above the piston, is subjected to the pressure normally existing in any one of the chambers 6, through a pipe or passage 17, while the other end, as for example, below 80 the piston 14, is subjected to the pressure normally existing at the throat of the diffuser 3 by connecting that end of the cylinder with the throat by means of a pipe or passage 18. Motion of the piston in response 85 to pressure exerted by the fluid entering through the pipe 17 is assisted by a coiled spring 19, which, if properly proportioned, will cause the piston to move, in response to variations in pressures in the chamber 6 and 90 at the throat 10, to shift the nozzle 4 in such a way that the effective area of the throat 10 will vary and will always be of the size required for the passage of the combined media issuing from the diffusers 8 and the 95 nozzle 12.

As the quantity of medium entering the ports 7 decreases, the amount of work necessary for accelerating the medium decreases until the condition is reached when no medium is entering the ports 7 and consequently no work of acceleration is required. As the amount of medium entering the ports 7 decreases, the pressure at the throat 10 also decreases with a tendency to equal that existing in the chamber 6, and the nozzle 12 is moved into proximity with the throat 10 of the diffuser 3. Since this movement of the nozzle is coincident with the diminution of work of acceleration required, I have 105 provided means for employing the motion of the nozzle in controlling the delivery of motive or expelling fluid to the nozzles 5. As illustrated, each nozzle 5 receives motive fluid from the central supply passage, 110 through a separate pipe or passage 22 and through a separate port 23. The delivery of fluid to each port 23 is controlled by the tubular portion 13, which is provided with ports 25, adapted to move into or out of register with the ports 23. With this arrangement, the area of each port 23 will vary with the position of the nozzle 12 in such a manner that just sufficient motive fluid is delivered to the nozzles 5 to maintain the work 115 120 125 130

of acceleration proportional to the amount of fluid admitted through the port 7.

In my copending application entitled "Fluid translating devices," filed September 5 14, 1914, and serially numbered 861,629, I have illustrated and claimed an ejecting device comprising a diffuser, a nozzle for delivering expelling or motive fluid through the diffuser, and means movable in response 10 to variations in the amount of medium to be expelled for varying the effective area of the diffuser. This means is illustrated as a movable plug or cone shaped member which is moved to different positions with relation 15 to the diffuser for the purpose of varying not only the effective area of the diffuser, but also the delivery of expelling fluid through the nozzle. The plug is shown as actuated by a piston which moves in response 20 to variations in pressure conditions within the diffuser.

In my copending application entitled "Fluid translating devices," filed September 14, 1914, and serially numbered 861,630, I have illustrated and claimed a two stage 25 ejector comprising a main diffuser, a main nozzle or set of nozzles for delivering expelling or motive fluid into and through the said diffuser, an auxiliary diffuser and an auxiliary nozzle for delivering expelling or 30 motive fluid into and through the auxiliary diffuser. The inlet to the auxiliary diffuser communicates with the source of medium to be expelled, and the auxiliary ejector performs 35 the double function of raising the pressure of the medium to be expelled prior to its delivery to the main diffuser and also of delivering a fluid filler to the main diffuser. The delivery of motive fluid by the 40 auxiliary nozzle is controlled by a movable plug or needle valve, which projects through the steam chamber into the inlet of the nozzle and is movable in response to variations in pressure conditions within the apparatus 45 for the purpose of varying the expansion ratio of the nozzle.

In my copending application entitled "Fluid translating devices," filed September 14, 1914, and serially numbered 861,633, I have illustrated and claimed an ejecting device including a diffuser communicating with 50 a source of medium to be expelled, and a nozzle for delivering motive or expelling fluid into and through the diffuser. The 55 nozzle is movable toward and away from the diffuser in response to variations in pressure within the ejecting device. This apparatus is essentially a single stage apparatus.

In my copending application entitled 60 "Fluid translating devices," filed September 14, 1914, and serially numbered 861,634, I have illustrated and claimed an ejecting device provided with a passage from which a medium is to be exhausted communicating 65 with a diffuser through which the medium

from the passage is expelled. A fluid delivery nozzle delivers expelling fluid through the diffuser and a means responsive to variations in the amount of medium entering the passage is provided for controlling direct 70 communication between the diffuser and the passage. As illustrated and claimed, a main or second stage includes a nozzle or set of nozzles which delivers expelling or motive fluid into and through a diffuser. The auxiliary or first stage is in open communication with the source of medium to be expelled and consists of at least one motive fluid nozzle and a diffuser receiving fluid from that nozzle and accomplishing a preliminary compression of the medium prior 75 to its delivery to the main diffuser. The main diffuser is provided with an inlet port or ports for medium to be expelled and this port is adapted to be placed in direct communication with the source of medium to be 80 expelled by means of a passage which in effect bypasses the first or auxiliary stage of the device. This passage is provided with a pressure responsive valve which responds 85 to variations in the amount of medium to be expelled and in this way controls the effective area of the bypass passage or, in other words, the amount of medium delivered directly from the source to the main diffuser. 90

In my copending application entitled "Fluid translating devices," filed September 14, 1914, and serially numbered 861,635, I have illustrated, described and claimed an ejecting device provided with a passage for 100 receiving a fluid to be compressed and a means for partially compressing the fluid from the passage. An ejecting device is arranged to receive the fluid from the compressing means and a means responsive to 105 variations in the amount of fluid entering the passage is provided for controlling the operation of the ejecting device. A first stage is illustrated as directly communicating with the source of medium to be expelled, 110 whereas the second stage not only communicates with the discharge of the first stage, but also communicates with the source of medium to be expelled through one or more ports formed within the diffuser of that 115 stage.

The first stage consists of a diffuser and one or more nozzles for discharging expelling or motive fluid into and through the diffuser and for thereby entraining medium 120 to be expelled. The second stage includes an annular nozzle and a movable diffuser which is provided with inlet ports at or near its throat. The ports in the diffuser of the second stage communicate with the source 125 of medium to be expelled through a passage which may be termed a bypass passage. Variations in the amount of medium entering the first stage or variation in the amount of medium to be expelled occasion variations 130

in the pressures existing at different points throughout the working passages of the ejector. These variations are employed for the purpose of shifting the position of the 5 movable diffuser and of thereby varying the effective area of the ports formed in the diffuser of the second stage. In other words, variations in the amount of medium to be expelled occasion variations in the effective 10 area of the bypass passage which places the second stage of the ejector in direct communication with the source of medium to be expelled. As illustrated and claimed, the diffuser is also capable of varying the effective 15 area of the nozzles which deliver motive fluid to the second ejector.

While I have described but one embodiment of my invention, it will be apparent that the drawings are more or less illustrative and that various changes, substitutions, 20 modifications, additions and omissions may be made in the apparatus illustrated without departing from the spirit and scope of the invention as set forth by the appended 25 claims.

What I claim is:

1. In combination in an apparatus of the character described, a diffuser, a chamber communicating with the diffuser receiving 30 medium to be expelled, a main delivery nozzle for delivering expelling fluid through the diffuser, an accelerating nozzle for delivering expelling fluid through the diffuser, and means responsive to variations in the 35 amount of medium entering the chamber for controlling the operation of said main nozzle and the delivery of fluid through said accelerating nozzle.

2. In combination in an apparatus of the 40 character described, a chamber receiving medium to be ejected, a diffuser communicating therewith through which the medium is ejected, a main nozzle for delivering expelling fluid through the diffuser, an accelerating nozzle for delivering expelling fluid through said diffuser, and means responsive to variations in the amount of medium to be expelled for moving said main nozzle relatively to said diffuser and for controlling 45 the delivery of fluid through said accelerating nozzle.

3. In combination in an ejector, a diffuser, a main impelling fluid delivery nozzle aligned with the diffuser and accelerating nozzles 50 around the main nozzle and discharging into the diffuser.

4. In combination in an ejector, a diffuser, a main nozzle for delivering a jet of impelling fluid into the diffuser, and means 55 for delivering accelerating impelling fluid around said main jet and into said diffuser.

5. In combination in an ejector, a diffuser, a chamber receiving fluid to be expelled and communicating with the diffuser, a main nozzle for delivering expelling fluid 60

into and through the diffuser, accelerating nozzles located around the main nozzle for delivering expelling fluid into and through the diffuser, and means responsive to variations in the amount of fluid entering the 70 chamber for controlling the operation of the accelerating nozzles.

6. In combination in an ejector, a diffuser, a chamber receiving fluid to be ejected, a main nozzle for delivering expelling fluid into and through the diffuser, at least one accelerating nozzle operating in conjunction with the main nozzle on fluid entering said chamber and to be expelled, and means responsive to variations of pressure within said chamber for controlling the operation of the main nozzle and of said accelerating nozzle.

7. In combination in an ejector, a diffuser, a chamber receiving fluid to be ejected, a main nozzle for delivering expelling fluid into and through the diffuser, at least one accelerating nozzle operating in series with the main nozzle on fluid entering said chamber and to be expelled, and means responsive to variations in the amount of fluid to be expelled entering said chamber, for varying the relative positions of the diffuser and the main nozzle and for controlling the delivery of fluid to the accelerating nozzle.

8. In combination in an ejecting device, an accelerating ejector comprising a mixing chamber communicating with a source of fluid to be expelled, a diffuser communicating with said chamber, and a nozzle for expanding and discharging motive fluid at a high velocity into and through said chamber and diffuser, a second diffuser located at an angle to the first diffuser and into which the first mentioned diffuser discharges, and an expansion nozzle for expanding fluid to the pressure at the inlet to the second diffuser and for discharging the fluid so expanded into and through the second diffuser.

9. In combination in an ejecting device, a chamber having an inlet port for medium to be ejected, a diffuser communicating with said chamber, a nozzle for discharging expelling fluid through said diffuser, a second diffuser communicating with the outlet of the diffuser, a second nozzle for discharging expelling fluid through said second diffuser, and means for varying the position of said second nozzle with relation to said 115 second diffuser, in response to variations in pressure within the device.

10. In combination in an ejecting device, a chamber having an inlet port for fluid to be ejected, a diffuser communicating with said chamber, a nozzle for discharging a stream of motive fluid into said diffuser, a second diffuser communicating with the outlet of the first, a second nozzle for discharging motive fluid into said second dif- 125

- fuser, and means for shifting the position of the second nozzle relatively to the inlet of the second diffuser.
11. In combination in an ejecting device, 5 a chamber having an inlet for medium to be expelled, a diffuser communicating with said chamber, a nozzle for discharging fluid through said diffuser, a second diffuser communicating with the first ejector, and means for varying communication between the first and the second diffuser.
12. In combination in an ejecting device, 10 a diffuser, a main nozzle axially aligned with said diffuser for delivering a jet of impelling fluid into and through the diffuser, accelerating nozzles located around the main nozzle and discharging into the diffuser, and means for controlling the delivery of fluid to the auxiliary nozzles.
13. In combination in an ejecting device, 15 a diffuser, a main nozzle axially aligned with said diffuser for delivering a jet of impelling fluid into and through the diffuser, accelerating nozzles located around the main nozzle and discharging into the diffuser, and means for controlling the delivery of fluid to the auxiliary nozzles in response to variations in pressure within said diffuser.
14. In combination in an ejecting device, 20 a diffuser, a main nozzle axially aligned with said diffuser for delivering a jet of impelling fluid into and through the diffuser, accelerating nozzles located around the main nozzle and discharging into the diffuser, and means for controlling the delivery of fluid to the auxiliary nozzles in response to variations in pressure within said device.
15. In combination in an ejecting device, 25 a main diffuser, a main nozzle for discharging expelling fluid into and through said diffuser, accelerating nozzles located around the main nozzle, and discharging into said main diffuser, and a separate diffuser between each auxiliary nozzle and the main diffuser.
16. In combination in an ejecting device, 30 a main diffuser, a main impelling fluid delivery nozzle axially aligned with the diffuser, accelerating nozzles located around said main nozzle and discharging into the main diffuser, a separate diffuser between each accelerating nozzle and the main diffuser, and means for controlling the delivery of expelling fluid to the auxiliary nozzles.
17. In an ejector, a plurality of ejectors operating in parallel on medium to be expelled, each comprising a chamber having an inlet port for fluid to be expelled, a diffuser communicating with said port, and a nozzle 60 for discharging expelling fluid through the diffuser, in combination with a main diffuser with which all the diffusers of said ejectors communicate.
18. In an ejecting device, a plurality of 65 ejectors operating in parallel on medium to be expelled, a diffuser into which said parallel operating ejectors discharge, and means for delivering a jet of expelling fluid into and through said diffuser.
19. In an ejecting device, a diffuser, a main impelling fluid delivery nozzle movable toward and away from said diffuser, and a plurality of accelerating nozzles around the main nozzle and discharging 70 into said diffuser.
20. In an ejecting device, a diffuser, a main impelling fluid delivery nozzle movable toward and away from said diffuser, a plurality of accelerating nozzles surrounding the main nozzle and discharging into the diffuser, and means responsive to variations in pressure within the diffuser for varying the position of the main nozzle.

In testimony whereof, I have hereunto 85 subscribed my name this 21st day of August, 1914.

HENRY F. SCHMIDT.
